UNITED STATES PATENT OFFICE.

HERBERT M. STURGIS, OF KANSAS CITY, MISSOURI.

LOOSE-LEAF BOOK.

No. 873,106.

Specification of Letters Patent.

Patented Dec. 10, 1907.

Application filed October 16, 1906, Serial No. 339,160. Renewed September 24, 1907. Serial No. 394,412.

To all whom it may concern:

Be it known that I, HERBERT M. STURGIS, a citizen of the United States, residing at Kansas City, in the county of Jackson and 5 State of Missouri, have invented certain new and useful Improvements in Loose-Leaf Books, of which the following is a specification.

This invention relates to loose leaf books 10 of that class in which the leaf-holding rings are held open or closed with a yielding pressure and my object is to produce a device of this character in which the anchoring elements may be bound to the cover and the 15 leaf holding elements be subsequently connected thereto easily and quickly and also be removed therefrom if desired.

A further object is to produce bars to 20 which the hooks can be easily and quickly secured so firmly and reliably as to be incapable of working loose under any strain to which the book may be subjected by a fall or from opening or closing the rings.

A still further object is to produce a loose 25 leaf book which will operate efficiently and reliably, is of ornamental and attractive appearance and can be manufactured economically.

With these general objects in view and 30 others as hereinafter appear the invention consists in certain novel and peculiar features of construction and organization as hereinafter described and claimed; and in order that it may be fully understood reference is to be had to the accompanying drawings, in which—

Figure 1, is a sectional perspective view of 40 a loose-leaf book when open and with the leaves omitted. Fig. 2, is a detail perspective view of the anchor plate. Fig. 3, is an enlarged cross section taken on the line III—III of Fig. 1. Fig. 4, is a similar view with the rings open and the cover and anchoring elements omitted. Fig. 5, is a sectional perspective view of one of the hook-carrying bars with the hooks omitted. Fig. 6, is a sectional perspective view of one of the hooks. Fig. 7, is a detail perspective view of one of the springs. Fig. 8, is a sectional 45 view of a modified form of hook-carrying bar. Fig. 9, is a cross section of the hook-carrying bars with the hooks omitted, and showing a pin and slot connection between the bars to insure synchronous movement 50 thereof. Fig. 10, is a side view of a semi-elliptic or modified form of spring.

In the said drawings, where like reference numerals identify corresponding parts, 1 indicates an anchor plate of segmental form in cross section and rounded by preference at 60 its ends and near the latter slit inwardly at opposite points as at 2 so that the rounded ends may be bent vertically upward to form end walls 3, which end walls are preferably provided with holes 4.

5 indicates a pair of elliptic springs corresponding by preference in size and contour to the end walls 3 and provided in their ends by preference with holes 6, rivets 7 being secured in the holes 4 and 6 to secure the 70 springs reliably to the inner sides of said end walls, the rivets fitting loosely in either the end walls or the springs in order to permit the latter to expand and contract.

8—8 indicate a pair of flattened tubular 75 bars which conjointly are about equal in width to the length of the elliptic-spring openings, and each of said bars are of length to project at their ends into said openings, the said projecting ends of the bars being 80 preferably of reduced thickness as at 9 with their outer ends preferably rounded as at 10 so as to fit snugly and find journals in the opposite extremities of the openings of said springs.

11—12 indicate segmental hooks of the type common in loose leaf books, their free or upper ends being adapted to interlock together to form complete rings. Their opposite ends extend into the tubular bars 90 through openings 13 in their upper walls as in the preferred construction, or in their outer edges as in the modified form of bar shown by Fig. 8. The inner ends of said hooks are preferably reduced to form sub- 95 substantially rectangular tongues 15 to fit non-rotatably in correspondingly shaped holes 14 in the inner walls or edges of the tubular bars and be riveted therein so as to guard against dislocation. By this construction I provide 100 hook-carrying bars in which it is absolutely impossible for the hooks to have any lateral play or movement and which are so stiff and rigid throughout that any outward pull or pressure applied on one pair of hooks is distributed upon all of them so that it is impossible for one pair of hooks to move slightly apart without all partaking of such movement in equal degree. In all other devices of this class of which I have knowledge the 110 bars 8 are of flat thin metal and on any outward pull applied on either of the end sets of

hooks will yield or twist slightly and permit said hooks to open a little before the hooks at the opposite end or the intermediate hooks will move. As a result of this leaves 5 of the books equipped with such devices occasionally become loose at one end and are therefore more apt to be torn in the ordinary handling of the book.

In assembling the parts of the book the 10 companion hooks are fitted together at their upper ends and as a result the bars assume substantially the position shown in Fig. 3, in which position the springs 5 may be expanded in the direction of their length, the 15 tendency of the springs to contract transversely or in their direction of their greatest length holding the hooks yieldingly interlocked at their upper ends and with the inner upper corners of the bars in engagement. 20 When the rings are opened by pulling outward upon a pair of the oppositely disposed hooks, said upper corners, in the upward rocking movement of the bars, elongate the springs in the direction of their length and as 25 said engaging corners pass above the horizontal plane of the bearing edges 10 the spring contracts in the direction of its length until the inner walls or edges of the tubular bars come squarely together as shown in Fig. 30 4, in which position they are held by the retractile tendency of the springs, and in this connection it will be noted that because of the depth of the inner edges or walls, the upward and downward movements of the bars 35 is synchronous, though if desired suitable means may be provided for slidingly locking said bars at their inner edges, one exemplification of such means being shown in Fig. 9, where it will be noticed the inner edge of one 40 bar is provided with a slot 16 and the corresponding edge of the other with a pin or tongue 17 slidingly engaging said slot.

The anchor plate can be secured to the 45 cover A in any suitable manner, the preferred method being to place a strip of cloth or equivalent material 18 upon the middle of the cover, then place thereon a metal plate 19 segmental in cross section and provided at its side margins with inwardly disposed 50 and upwardly projecting hooks 20, and next stretch loosely over said last-named plate the binder strip 21 of thin flexible leather or cloth and secure the opposite edges of said binder strip to the inner sides of the cover 55 in the usual or any preferred manner. The anchor plate is then by preference placed upon the binder strip and pressure is applied to spring or slip it into engagement with the hooks 20, the binding strip being of course 60 interposed between the anchor plate and the hook-equipped plate. When the anchor plate is thus secured the hooks 20 are pressed or crimped downward to effect a permanent union with said plate. It is preferred that 65 the anchor plate be bound to the cover be-

fore the bars and the springs encircling their ends are secured by the rivets 7 or otherwise to the end walls of said plate. By this method it will be seen that the cover may be equipped with the anchor plate in the bindery and that the remaining elements may be subsequently secured to the anchor plate easily, quickly and cheaply. The book will be provided with the usual perforated leaves, not shown, to be placed upon or removed 75 from the hooks in the usual manner.

In Fig. 10, I show a modified form of spring, the same being a semi-elliptic spring 22 which in all essential particulars comprises the upper half of one of the springs 5, 80 the cavities 23 forming the bearing points for the bearing edges 10 of the reduced ends 9 of the tubular bars 8. The spring is also provided with holes 24 to receive the rivets 7 or equivalent devices for securing it to the 85 end walls 3 of the anchor plate.

From the above description it will be apparent that I have produced a loose leaf book possessing the features of advantage enumerated as desirable and which obviously 90 may be modified in various particulars without departing from the spirit and scope of the appended claims.

Having thus described the invention what I claim as new and desire to secure by Letters-Patent, is:—

1. In a loose leaf book, a tubular bar having a pair of openings, and a hook extending through one of said openings into said bar and riveted in the other opening. 100

2. In a loose leaf book, a flattened tubular bar provided with openings one of which has angular sides, and a hook extending through one of said openings into the bar and having its base end reduced and fitting non-rotatably and riveted in said angular opening. 105

3. In a loose leaf book, a pair of hook-carrying bars, an integrally formed elliptic spring inclosing one end of the hook-carrying bars, and a similar spring inclosing the other end of the hook-carrying bars, the opposite ends of the elliptic openings of said springs forming bearings for the outer edges of the inclosed portions of the bars and holding said bars yieldingly together at their inner edges 110 with the upper ends of the hooks apart or with the upper ends of the hooks together and the inner upper edges of the bars together and disposed below the plane of their outer edges. 115

4. In a loose leaf book, an anchor plate of segmental form in cross section and provided with upwardly projecting end walls, springs fitting and secured against the inner sides of the end walls, bars having their ends projecting into the openings of said springs and pressed by the latter yieldingly together, and sets of hooks rigidly secured to and projecting upwardly above said bars and adapted to be held yieldingly together or apart by the 120 125 130

contractile pressure of the springs on the bars.

5. In a loose leaf book, a pair of bars equipped with hooks, curved springs engaging 5 the outer edges of the ends of said bars and pressing the latter yieldingly together, an anchor plate below the bars and provided at its ends with walls projecting upwardly at the outer sides of said springs, and means for fastening the latter to said walls without preventing 10 said springs from exerting continuously a yielding inward pressure on the bars.
6. In a loose leaf book, a pair of bars equipped with hooks, curved springs engaging 15 the outer edges of the ends of said bars and pressing the latter yieldingly together, an anchor plate below the bars and provided at its ends with walls projecting upwardly at the outer sides of said springs, and means for fastening 20 the latter to said walls without preventing said springs from exerting continuously a yielding pressure on the bars, in combination with a plate underlying the anchor plate and provided with hooks extending upward 25 and inward around and over the side edges of said plate, a cover, and a binder strip hooked around and in said hooks and interposed and clamped between the same and the anchor plate and secured at opposite sides of 30 said plates to the cover.
7. In a loose leaf book, a cover, a plate secured to the cover and provided with upwardly projecting and inwardly disposed hooks at its sides, a binder strip secured at 35 opposite sides to the inner side of the cover
- and hooked around and within said hooks and resting upon said plate, and an anchor plate upon said binder strip and having its side edges projecting into the hooks with the binder strip interposed and clamped tightly 40 between them.
8. In a loose leaf book, a cover, a plate secured to the cover and provided with upwardly projecting and inwardly disposed hooks at its sides, a binder strip secured at 45 opposite sides to the inner side of the cover and hooked around and within said hooks and resting upon said plate, an anchor plate upon said binder strip and having its side edges projecting into the hooks with the 50 binder strip interposed and clamped tightly between them, a pair of curved springs carried by and at opposite ends of the anchor plate, and a pair of hook-carrying bars pressed yieldingly together by said springs 55 with the upper ends of their hooks together or apart.
9. In a loose leaf book, a pair of tubular bars pressed yieldingly together, one of the bars having a slot in its inner edge and the 60 other a tongue projecting from its inner edge through said slot and adapted to slide therein when the bars are rocked in a vertical plane.

In testimony whereof I affix my signature, in the presence of two witnesses.

HERBERT M. STURGIS.
